PROCESS OF PREPARING CARBON DOPES

Filed March 23, 1927

FIG. I.

FIG. II.

FIG. III.

INVENTOR:

HAROLD W. A. DIXON,

*By Arthur C. Page,
Attorney.*

UNITED STATES PATENT OFFICE.

HAROLD W. A. DIXON, NEW YORK, N. Y.

PROCESS OF PREPARING CARBON DOPES.

Application filed March 23, 1927. Serial No. 177,727.

My invention is particularly adapted for the commercial production of the colloid compositions which are used for coating carbon paper and similar fabrics. Such compositions primarily include particles of solid matter such as carbon and dye substances, in suspension in a waxy substance, which is liquid when hot and during the spreading of the coating upon the desired web or textile fabric, 10 and thereafter becomes solid when chilled. Ordinarily, the carbon, coloring matter, and wax-like ingredients of the prospective coating are primarily mixed, in a more or less lumpy state, in kettles which are heated, by steam or otherwise, and provided with means to agitate their contents. The crude magma thus formed is more or less granular and irregular in composition. Therefore, it must be further treated to reduce the size of the 15 particles and render the mass more homogeneous. An essential step in such treatment is the repeated passage of the mass between the members of a milling couple, until the particles in the colloid are reduced to dimensions of the order of, say, one micron. During such treatment, it is necessary, or at least highly desirable, to maintain the mass heated above atmospheric temperatures, to effect such treatment economically.

Therefore, I have devised an apparatus including a suitable milling couple in conjunction with means for repeatedly passing the colloid through said mill, and that apparatus is the subject matter of my application 35 Serial No. 177,723 filed March 23, 1927, for Letters Patent of the United States. I find it convenient to utilize such apparatus in the method herein claimed; the essential feature of the latter being that the conduits 40 and passageways throughout the apparatus are preheated and any waxy deposits therein dissolved and removed by and with hot oil which is thereafter used as one of the ingredients of the next batch of colloid which is 45 passed through the apparatus to effect comminution of its particles.

In the drawings; Fig. I is a diagrammatic plan view of apparatus including a milling couple and means for repeatedly progressing the liquid between the opposed surfaces thereof.

Fig. II is a fragmentary and somewhat diagrammatic sectional view of a milling couple of a form which I prefer to employ to present 55 metallic surfaces in opposed spaced relation,

in contact with the opposite faces of a film of the colloid progressed between them.

Fig. III is a fragmentary and somewhat diagrammatic sectional view of a modified form of milling couple which may be substituted for that of Fig. II, in the apparatus shown in Fig. I.

Fig. IV is a plan view of the valve structure indicated in Fig. I, but with the rotary valve body turned to the alternative position.

Referring to Fig. I; the two colloid containers 1 and 2, which are preferably steam heated kettles or tanks, are arranged to be alternately connected, by the valve structure 70 3, with the mill 4 so that, with said valve in the position shown, the colloid is withdrawn from the container 1, passed between the milling couple 5 and 6 in said mill, and discharged into the container 2, by the operation 75 of the pressure pump 8 and suction pump 9 and, with the valve structure 3 in an alternative position shown in Fig. IV, the colloid is withdrawn from said container 2, passed between the members 5 and 6 of said 80 milling couple, in the same direction as before, but returned to said container 1. Said valve may be turned by the handle 7 to the extent limited by the stop lugs 10.

To effect such operation; said container 1 85 is provided with the conduit 11, controlled by the cock 12 and leading to the port 13 in the end closure 14 of the valve casing 15. Said port 13 is in registry with one end of the duct 17 which extends through the rotary valve 90 body 18 and then in registry with the port 20 in said closure 14 which is provided with the conduit 21 leading, through said pressure pump 8, to the inlet port 22 in the casing of said mill 4. Said port 22 opens into the mill 95 pressure chamber 23, and the colloid passes thence through the interstice 25 between said milling members 5 and 6, which are continuously maintained in axially spaced relation. The conoidal configuration of the opposed 100 metallic milling surfaces of said members 5 and 6 is such that when they are rotated at sufficient velocity, there is a centrifugal effect which progresses the colloid in an evolute path into the vacuum chamber 26 from which 105 it is exhausted, through the conduit 28, by said pump 9, so as to produce a partial vacuum in said vacuum chamber 26. Said conduit 28 leads through said exhaust pump 9 to the port 29 in said end closure 14 of the 110

valve casing 15. Said port 29 is in registry with the end of the duct 30 which extends through said rotary valve body 18 and then in registry with the port 31 in said closure 5 14 which is provided with the conduit 33 controlled by the cock 34 and leading into said container 2.

In the form of mill shown in Fig. III, the conduit 21 discharges into the pressure chamber 36 within the rotor 37, of the milling couple, which has radial ducts 38 leading to its cylindrical perimeter, which is opposed to the internal cylindrical surface of the stator 39. There is a cylindrical interstice 40 between 10 the opposed milling surfaces of said milling couple 37 and 39 through which the milled colloid passes into the vacuum chamber 42 comprising the spaces on both of the axially opposite sides of said rotor 37, from which 15 the milled colloid is exhausted into the conduit 28. In that form of mill; rotation of the milling member 37 has such centrifugal effect upon the colloid passing through it from the chamber 36 as to continually present such colloid under pressure at the interstice 40; but 20 there is no direct centrifugal effect upon the film in said interstice tending to discharge it from between the members of the couple. 25

However, it is to be understood that any 30 suitable mill structure may be included in the apparatus above described with reference to Fig. I.

In accordance with my method; batches of colloid such as the carbon dope or other color 35 pastes used for coating paper or textile fabrics, as above contemplated, are successively mixed and treated in the apparatus described and discharged therefrom after repeated passage between the milling couple therein until 40 the particles of the colloid are disintegrated and dispersed therein to the desired degree. The first step in said process is to heat in one 45 of the containers 1 or 2 aforesaid, a sufficient quantity of oil to be used in such a single batch. The second step is to circulate the hot oil through the conduits and passageways of the apparatus to be traversed by the colloid, by operating said pumps. The effect of such 50 circulation is to not only heat the apparatus to such temperature as to permit the colloid batch to be progressed therethrough without solidification, but also dissolves out, into the oil, any waxy matter which has been deposited in the apparatus. At the conclusion of said 55 second step; the hot oil having been deposited in one of said containers, the third step is to add thereto the other ingredients to form the desired batch of colloid which, of course, is heated to the desired degree. The fourth 60 step is to circulate the colloid through the mill until the particles and oil globules therein have been comminuted and dispersed in the colloid to the desired degree.

Thereupon, the milled colloid may be withdrawn 65 from the container 1 or 2 in which it

has been deposited, and the apparatus may be charged with a fresh batch of oil and the operation above described repeated.

The valve structure above described is the subject matter of my copending application 70 Serial No. 177,725 filed March 23, 1927, for Letters Patent of the United States, and may be conveniently employed as above contemplated to control the conduits leading to and from said containers 1 and 2. However, it 75 is obvious that said conduits may be otherwise controlled.

I have found it desirable to provide means to vary the rate of rotation of the rotor from one thousand revolutions to more than twenty 80 thousand revolutions per minute; and to vary the clearance between the milling surface of said rotor and the opposed surface of the stator from .002 inch up ward, according to the materials in the colloid and the desired 85 degree of comminution thereof.

Although I find it convenient to use the oil ingredient of a carbon dope colloid as the medium for preheating and cleansing the apparatus; my invention is not limited to col- 90 loids containing oil, but is applicable to col- loids comprising other liquids which may be used for the heating medium, for instance, textile emulsions, dyes and cements in which the principal liquid ingredient is water. In 95 such cases the water or other liquid ingredient of the prospective colloid may be used as the heating and cleansing medium.

Therefore, I do not desire to limit myself to the precise details of construction, arrangement or procedure above set forth, as it is obvious that various modifications may be made therein without departing from the essential features of my invention, as defined in the appended claims. 105

I claim:

1. A process of preparing, in successive batches, a colloidal composition, including oil and wax, which solidifies at atmospheric temperatures, which consists in charging a container with a sufficient quantity of oil for one batch; preheating said oil above atmospheric temperatures; progressing the hot oil from said container to another container, through apparatus including a pressure pump, a relatively rotary milling couple, an exhaust pump, and conduits connecting them, and thereby preheating said apparatus to such temperature as to prevent solidification of such colloidal composition therein; retaining said hot oil in the apparatus while adding to said oil the other ingredients to form a single batch; and progressing said batch alternately from one of said containers to the other, through said apparatus, while thus heated, until the globules of oil and particles of other matter in said batch are comminuted and dispersed therein to the desired degree. 110

2. A process of preparing, in successive batches, a colloidal composition, including oil 115

and wax, which solidifies at atmospheric temperatures, which consists in charging a container with a sufficient quantity of oil for one batch; preheating said oil above atmospheric 5 temperatures; progressing the hot oil from said container to another container, through apparatus including a relatively rotary milling couple, and thereby preheating said apparatus to such temperature as to prevent 10 solidification of such colloidal composition therein; retaining said hot oil in the apparatus while adding to said oil the other ingredients to form a single batch; and progressing said batch alternately from one of 15 said containers to the other, through said apparatus, while thus heated, until the particles of matter in said batch are comminuted and dispersed therein to the desired degree.

3. A process of preparing, in successive 20 batches, a colloidal composition which solidifies at atmospheric temperatures, which consists in charging a container with a sufficient quantity of a liquid ingredient for one batch; preheating said liquid above atmospheric 25 temperatures; progressing the hot liquid from said container to another container, through apparatus including a relatively rotary milling couple, and thereby preheating said apparatus to such temperature 30 as to prevent solidification of such colloidal composition therein; retaining said hot liquid in the apparatus while adding to said liquid the other ingredients to form a single batch; and progressing said batch alternately from one of said containers to the other, through said apparatus, while thus heated, until the particles of matter in said 35

batch are comminuted and dispersed therein to the desired degree.

4. A process of preparing, in successive 40 batches, a colloidal composition, including liquid and solid matter, which consists in charging a container with a sufficient quantity of liquid for one batch; preheating said liquid; progressing the heated liquid through 45 apparatus including a relatively rotary milling couple, and thereby preheating said apparatus; retaining said heated liquid in the apparatus while adding to said liquid the other ingredients to form a single batch; and 50 progressing said batch alternately from one of said containers to the other, through said apparatus, while thus heated, until the particles of matter in said batch are comminuted and dispersed therein to the desired degree. 55

5. A process of preparing a colloidal composition, including liquid and other matter, which consists in preheating a liquid ingredient for said colloidal composition; progressing the heated liquid through apparatus 60 including a relatively rotary milling couple, and thereby preheating said apparatus; retaining said heated liquid in the apparatus while adding to said liquid the other ingredients for the colloidal composition; and 65 progressing said colloidal composition through said apparatus, until the particles of matter are comminuted and dispersed in the colloidal composition to the desired degree.

In testimony whereof, I have hereunto 70 signed my name at New York, New York, this 23rd day of February, 1926.

HAROLD W. A. DIXON.
